UNITED STATES PATENT OFFICE.

RAY L. STOKELY, OF FLORAL PARK, NEW YORK, ASSIGNOR, BY MESNE ASSIGNMENTS, TO WESTERN ELECTRIC COMPANY, INCORPORATED, A CORPORATION OF NEW YORK.

TELEPHONE-EXCHANGE SYSTEM.

Application filed April 9, 1925. Serial No. 21,756.

This invention relates to telephone systems, and more particularly to improvements in circuit arrangements for enabling toll operators to build up toll connections to 5 automatic subscribers' lines.

A general object of this invention is to improve the operating efficiency and to effect equipment economy in circuits of this character.

In present trunking systems of this type the toll lines incoming to a toll operator's position, are either equipped with composite ringers or else merely arranged to transmit ordinary ringing current signals. In the 15 first instance, the 16 cycle ringing current applied by the composite ringer to a toll operator's cord circuit, is usually of such value as to cause disturbances in the circuits beyond if, for example, these signals are applied as a re-ringing signal to the toll operator when a cord circuit is connected through to an outgoing trunk leading to an automatic exchange, and the called subscriber has already been connected and has his receiver off the hook. That is, this re-ringing signal may, in this case, operate the regular 20 ring-up relay in the trunk circuit, and consequently cause the ringing relay to operate and apply ringing current to the called subscriber's line. On the other hand, the ring-up relay may operate in case the re-ringing signals from an ordinary toll line are unusually strong, which might be due either to disturbances on a particular line or to the 25 fact that the line itself is unusually short. Again, if the connected trunk line happens to be short, the incoming re-ringing signals from either of these two types of lines may be sufficiently strong to cause the ring-up 30 relay to function.

Heretofore a special ring-up relay was used provided with a weighted armature so arranged in relation to the contact springs of the relay that they would not operate in 45 response to incoming re-ringing signals; but, on the other hand, would operate satisfactorily in response to signaling current outgoing from a toll operator's cord circuit that are sent out in the usual manner for calling 50 of subscribers' lines. However, relays of this type in which the magnetic effect on the armature is directly proportional to the incoming current may not prove entirely satisfactory under all circumstances as, for 55 example, when the attenuation of the ring-

ing signals outgoing from the toll operator's position, are such as to barely operate the weighted armature, in which case this armature would tend to fluctuate for a short interval before it finally settles down to positively operate the contacts. Such uncertain operation of the ringing equipment would consequently be unsatisfactory.

Another object of this invention is therefore to provide ringing equipment in trunk 60 lines, outgoing from a toll operator's position and terminating at automatic exchanges, that responds positively to ringing signals originating at a toll operator's cord circuit and does not operate at all when re-ringing signals are applied to the operator's cord circuit from either a toll line equipped 70 with a composite ringer or an ordinary toll line.

To accomplish these and other objects of 75 the invention, there is provided in accordance with one feature thereof, a ring-up relay in the circuit arrangement, for the operation of the ringing relay, in which the ring-up relay is provided with two springs 80 of relatively different stiffness, the stiffer of these springs being arranged to complete an energizing circuit for the slow-release ringing relay and the other more flexible spring, which naturally will operate before and release after the stiffer spring, is arranged to close a holding circuit for the ringing relay after the original operation thereof. By means of this arrangement, it will be seen that any ringing signal that is of sufficient 85 value to once operate the stiffer spring and cause the operation of the ringing relay, will also cause the locking circuit for the ringing relay to be closed, and any subsequent fluctuations of the stiffer spring that 90 might open the original energizing circuit will not ordinarily cause the ringing relay to release, this being partly due to the slow release characteristics of the ringing relay itself but primarily due to the tendency of 95 the more flexible spring of the ring-up relay to remain operated after the less flexible spring has released.

To further improve the efficiency of this 100 usual type of ring-up relay, the toll lines and composite ringers may be so arranged that the 16 cycle ringing current may be applied to the toll operator's cord circuit at more accurate and adjusted values. For this 105 purpose, compensating resistances may be 110

included between the ringing source and the line, or the output of the ringing source itself may be correspondingly adjusted.

Another feature of the invention resides in the provision of means for further elimination of disagreeable clicks in a subscriber's receiver connected to a trunk line when the ringing relay operates. To this end, use is made of what are called "continuity springs" on the ringing relay, i. e., by so arranging the contact springs on this relay that the ringing current will be connected to the subscriber's line before the talking battery is disconnected therefrom, and vice versa.

To accomplish the general object of increasing the efficiency of circuits of this type, another feature of the invention resides in means for positively disconnecting the ringing current from a called subscriber's line the moment the subscriber lifts the receiver from the hook on answering a call, even though the ringing key at the toll operator's position may still be operated thus entirely eliminating any possibility of the subscriber being annoyed by having to listen to the ringing after the receiver has been removed.

Still another feature of the invention reside in the provision of an arrangement for connector circuits for preventing a false advance of the brushes of a connector switch from the terminals of the last trunk line of a group of P. B. X. trunk lines to the terminals of the first trunk line of the next succeeding group of trunks or of the next succeeding subscriber's line in case this test trunk line is busy, that is, if a second connector switch is already connected therewith.

Other features will appear hereinafter. Having described in a brief way the operation of the system embodying the present invention, a more detailed description will now be given in connection with the accompanying drawings in which:

Fig. 1 shows a toll operator's cord circuit arranged in accordance with this invention associated with two different types of incoming toll lines; Fig. 2 shows an outgoing trunk circuit adapted for association with the cord circuit and an automatic selector switch in which this trunk circuit terminates at an automatic exchange; while Fig. 3 shows a connector circuit at this exchange and a called subscriber's line.

When plug 100 of the toll operator's cord circuit is inserted in jack 101 of a ringdown toll line in response to the lighting of a line lamp (not shown), relay 102 operates in an obvious circuit. The operation of relay 102 in turn operates relay 103, under control of relay 104. The operation of relay 103 prevents relay 105 from operating and also the lighting of supervisory lamp 106. The toll operator having received the number of the desired line at her telephone set 150, which

is connected to the cord circuit by operation of the talking key 151, touches the tip of plug 107 to the sleeve of jack 200 (Fig. 2) to select an idle trunk line leading to the machine switching office in which the desired line terminates and if it is idle inserts the plug and operates the dialing key 115.

A busy condition of the trunk line is indicated by battery on the sleeve of the jack 200, which produces a click in the receiver 108 of the operator's telephone set 150 in the following manner: Battery on the sleeve, over the tip of the plug 107, outer left normal contacts of relay 109, inner left normal contacts of relay 110, through the left-hand winding of induction coil 112 to ground. Current in this circuit produces a click in the receiver 108 due to the flow of induced current in a circuit comprising the right-hand winding of induction coil 112, the upper and lower normal contacts of relay 113 and the winding of receiver 108.

The insertion of the plug 107 in jack 200 combined with the operation of dialing key 115 causes the operation of relays 109 and 202, the circuit of which can be traced as follows: battery, outer normal contacts of relay 116, left-hand winding of relay 109, lowermost alternate contacts of key 115, outer left normal contacts of relay 110, ring contacts of plug 107 and jack 200, outer left normal contacts of relay 201 and left-hand winding of relay 202 to ground. Relay 109, in operating, disconnects the cord circuit from the plug and connects the dial circuit, including dial 118, thereto instead.

The operation of relays 109 and 202 completes a series circuit for the operation of relays 203 and 119 which can be traced as follows: battery, normal contact of relay 120, winding of relay 119, right-hand winding and right alternate contacts of relay 109, sleeve contacts of the plug 107 and jack 200, left alternate contacts of relay 202 and right-hand winding of relay 203 to ground. The operation of relay 119 closes an obvious circuit for relay 116 which then operates, thereby closing the dialing loop including the tip and ring of the plug through the contacts of dial 118. Relay 203, in operating, connects battery at its left alternate contacts to the winding of relay 201 thereby causing its operation. Relay 201, in operating, opens at its outer left normal contacts the operating circuit for relay 202 and closes at its contacts 205, a holding circuit for this same relay which can be traced from battery, left alternate contacts of relay 203, right-hand winding of relay 202, contacts 205, relay 201 and to ground through the left-hand winding of relay 202. Relay 201, in operating, also closes its innermost alternate contacts thereby partially closing a bridge including relay 206 across the trunk conductors. The circuit is not completed,

however at this time as it is opened at the right-hand normal contacts of relay 203. Further, relay 201 in operating extends the trunk conductors to the distant office and also 5 locks up at its contacts 207 under control of relay 206.

The combined operation of relays 109, 116 and 201 closes the trunk circuit including 10 winding of pulsing relay 204 at the machine switching office. This circuit can be traced from battery, normal contacts of release magnet 208, right-hand winding of pulsing relay 204, outer left normal contacts of relay 211, contacts 213 of relay 212, resistance 15 214, contacts 215 of relay 212, ring conductor of the trunk, contacts 219 of relay 201, ring contacts of the jack 200 and plug 107, outer left normal contacts of relay 110, inner left alternate contacts of relay 109, 20 winding of polarized relay 120, contacts of the dial 118, inner alternate contacts of relay 116, outer left alternate contacts of relay 109, tip contacts of the plug 107 and jack 200, contacts 220 of relay 201, contacts 25 218 of relay 212, resistance 262 and contacts 221 of relay 212 to ground. Relay 204 operates in this circuit but polarized relay 120 does not operate at this time due to its connection in the circuit with respect to the 30 polarity of the battery at the machine switching office.

The operation of relay 204, closes at its right alternate contacts, an obvious circuit 35 for operating relay 222. Relay 222, in operating, closes its right alternate contacts 227 thereby preparing the energizing circuit including the pulsing contacts of relay 204 for the vertical or primary switch magnet 223. In this circuit is included relay 224. Relay 40 222, in operating, also closes an energizing circuit for relay 257 which may be traced as follows: ground, left alternate contacts of relay 222, outer right normal contacts of relay 248, outer right normal contacts of relay 211 and winding of relay 257 to battery. Relay 257 operates in this circuit for a purpose to be later described.

The next operation on the part of the operator, after having inserted plug 107 into 50 jack 200 is to turn the dial 118 to the first digit of the wanted number. As the dial returns to normal, the loop dialing circuit is interrupted a number of times corresponding to the digit selected and thereby causes the synchronous release of relay 204. This relay in turn closes the prepared circuit for the vertical magnet 223 which now also operates a corresponding number of times and in series with relay 224. It will be noted that 55 relays 222 and 224 are slow to release and although the circuits for these relays are alternately opened, they will be held operated during the pulsing. The circuit for operating relay 224 and magnet 223 can be 60 traced from battery, winding of magnet 223,

winding of relay 224, contacts 225 of relay 226, contacts 227 of relay 222 and right normal contacts of relay 204 to ground.

When the selector took its first step due to the energization of magnet 223, the "off-normal" switch 228 operated, thereby closing a circuit for the operation of relay 229 which can be traced as follows: battery, normal contacts of relay 208, contacts 230 of switch 228, winding of relay 229, contacts 231 of relay 224 and to ground at the left alternate contacts of relay 222. In attracting its right-hand armature, relay 229 locks itself up in a circuit including the normal contacts of rotary magnet 232 and its own right-hand alternate contacts. Relay 229, in operating, also closes a short circuit path around the winding of relay 226 which can be traced from ground, left alternate contacts of relay 222, the right-hand terminal of the winding 70 of relay 226 and from the left-hand terminal of this winding to ground at the right-hand alternate contacts of relay 229 to prevent this relay from operating at this time.

With each interruption of the dial contacts during the transmission of the first digit, the vertical magnet 223 will be energized and step the brushes to the desired level of the switch bank. Upon the cessation 90 of the impulses and the release of relay 224, which relay as stated held up during the pulsing, the circuit of the rotary magnet 232 is closed as follows: battery, winding of magnet 232, left alternate contacts of relay 229, contacts 233 of relay 224 and to ground at the left-hand alternate contacts of relay 222.

The energization of the rotary magnet 232 causes the brushes to be moved into contact with the terminals of the first 100 trunk and by interrupting at its normal contacts the locking circuit for relay 229 previously traced causes this relay to release which thus in turn breaks the energizing circuit of magnet 232. The switch will, therefore, come to rest on this first trunk if 105 it is idle—that is, if no ground is present on the terminal S. Under these circumstances, the short circuit across the terminals of the winding of relay 226 will also be opened when relay 229 releases and when the armature of magnet 232 restores to normal, relay 226 will operate in the following circuit:

ground, left alternate contacts of relay 222, winding of relay 226, normal contacts of magnet 232, winding of relay 229, contacts 230 of switch 238 and normal contacts of relay 208 to battery. Relay 226 operates in this circuit, but relay 229 which is marginal, will not operate at this time due to the high 115 resistance introduced into the circuit by the winding of relay 226.

If the first trunk on which the brushes land is busy, its sleeve contacts S are grounded. In this case, relay 229 releases as before 120 but relay 226 will not operate as it is still 125

short-circuited, this time through its own contacts 234 to ground on the S terminal instead of to ground over the right-hand alternate contacts of relay 229. When therefore the rotary magnet 232 releases its armature, relay 229 will again energize, but this time to the ground on the S terminal whereupon the rotary magnet will be again energized to step the brushes forward to the next trunk. The foregoing operations will be repeated until a non-busy trunk is reached.

When relay 224 operated on the first pulse of the digit dialed, its contacts 237 were closed thereby completing a circuit for the energization of relay 238 which can be traced as follows: battery, winding of relay 238, contacts 237 of relay 224 and to ground over the left alternate contacts of relay 222. Relay 238, in operating, locked up independent of the contacts 237 of relay 224 in the following circuit: battery, winding and inner right alternate contacts of relay 238, contacts 240 of relay 226 and to ground at the left alternate contacts of relay 222. Relay 238, in operating, also opens the circuits for relays 212 and 241 and shunts condenser 242 of repeating coil 243 by resistance 244 so that relay 300 (Fig. 3) in the connector associated with the trunk selected will therefore operate when the tip and ring conductors are closed by the operation of relay 226. It should be understood that additional selectors may be interposed between the connector and the selector shown in Fig. 2, depending on the capacity of the system, as is well known in the art.

When the brushes land on an idle trunk, relay 226 operates as before described and closes its left-hand contacts thereby extending the trunk through to the connector (Fig. 3). Relay 226, in operating, also opens at its contacts 225, the stepping circuit previously traced for the vertical magnet 223 and in closing its contacts 235, transfers the holding circuit for relay 238, previously described, to the control lead 308 completed to terminal C. Relay 238 is, therefore, now held energized over this control lead through a circuit which may be traced from ground at the left alternate contacts of relay 222, inner right alternate contacts of relay 226, sleeve brush of the selector, terminal S, conductor 306, contacts 307 of relay 301, control lead 308, terminal C, the control brush, contacts 235 of relay 226, inner right alternate contacts and the winding of relay 238 to battery.

The seizure of the trunk extending to the connector completes as stated an energizing circuit for the pulsing relay 300 which now may be traced as follows: battery, left-hand winding of relay 300, contacts 304 of relay 301, ring conductor 302, terminal R, corresponding selector brush, contacts 245 of relay 226, contacts 239 of relay 204, con-

tacts 247 of relay 248, lower right winding of repeating coil 243, resistance 244, contacts 250 of relay 238, upper right winding of repeating coil 243, contacts 252 of relay 248, contacts 254 of relay 226, a selector brush and corresponding terminal T, conductor 303, contacts 305 of relay 301 and the right-hand winding of relay 300 to ground. Relay 300 in energizing closes at its alternate contacts a circuit for relay 309 which may be traced from battery, right-hand winding of relay 309, alternate contacts of relay 300, contacts 310 of relay 301 to ground. Relay 309, in operating, locks at its inner right alternate contacts to ground on control lead 308 over contacts 311 of relay 312. Relays 300 and 309, in operating, open the circuit of the release magnet 313.

If now the toll operator manipulates the dial in accordance with the tens and units digits of the wanted subscriber's line, the following operation will take place. The return of the dial to normal in transmitting the second or tens digit impulses of the wanted number, interrupts the circuit of relay 300 at contacts 239 of relay 204. The armature of relay 300 follows these interruptions and in its turn closes at its normal contacts the circuit of the vertical magnet 314. The circuit closed by the first dial interruption or pulse is as follows: ground, contacts 310 of relay 301, normal contacts of relay 300, contacts 315 of relay 309, contacts 316 of "off-normal" switch 317 and windings of relay 318 and vertical magnet 314 to battery. The energization of vertical magnet 314 causes the brushes of the connector switch to move one step off normal whereupon the off-normal switch 317 operates and switches the impulse circuit of vertical magnet 314 over an alternate off-normal contact through the alternate contacts of slow to release relay 318, which relay operated in series with magnet 314 at the first impulse. Relay 318, in operating, also opens at its normal contacts the circuit of rotary magnet 319. Relay 318 due to its slow to release character, holds operated during the transmission of the succeeding pulses. As the pulses continue, magnet 314 elevates the brushes to the desired level and upon the cessation of the impulses, relay 318 releases and transfers the pulsing circuit from the vertical magnet to the rotary magnet 319.

The return of the dial to normal in transmitting the last or unit digit impulses, causes the relay 300 to be released, for each interruption of the dial contacts and thus cause the operation of the rotary magnet 319 to move the switch brushes into engagement with the desired line. Relay 320 is in series with magnet 319 and energizes on the first impulse, but due to its slow to release character holds operated during the remainder of the pulses of the series. Relay 320, in

operating, opens at its inner normal contacts, the operating circuit for relay 312, prepares the busy test circuit by closing its contacts 322, and opens the hunting lead at 5 its outer normal contacts.

As soon as relay 320 releases, at the end of the pulsing and if the called line is idle, a circuit is closed at contacts 321 of relay 320 for the operation of relay 301 which can be 10 traced as follows: battery, through the usual cut-off relay (not shown) associated with the called line, sleeve terminal 323, sleeve brush of the switch, contacts 321 of relay 320, contacts 324 of relay 325, contacts 326 of 15 relay 312, contacts 327 of relay 301, left alternate contacts of relay 309, left-hand winding of relay 301, sleeve conductor 306, terminal S (Fig. 2) the sleeve brush of the selector, inner right alternate contacts 20 of relay 226 and to ground at the left alternate contacts of relay 222. Relay 301 and the cut-off relay of the called line, operate in this circuit. Relay 301, in operating, removes ground at its contacts 25 307 from the control lead 308 which extends back to the selector, thereby causing the release thereat of relay 238. Relay 238, in releasing, closes at its left normal contacts, an obvious energizing circuit for relay 212, 30 which relay, in operating, reverses and reduces the current flowing back over the trunk to the dial circuit of Fig. 1 by including resistances 214, 219 and 217 in the circuit and thereby causing the energization of polarized 35 relay 120. This relay, in turn, causes relays 119, 116 and 109 to release. Relay 109 in turn disconnects the dial circuit from the trunk and connects the cord circuit thereto instead. When relay 109 releases, supervisory relay 124 operates due to the fact that 40 it is bridged across the tip and ring conductors of the cord circuit which is now connected to the trunk and supplied with battery from the distant machine switching office. Relay 124, in operating, causes supervisory lamp 125 to light as an indication to 45 the operator that the line dialed has been seized and that everything is in readiness for her to ring.

50 As before mentioned, the release of relay 238 was caused by the operation of relay 301 which removed ground from the control lead. However, when relay 238 retracts its inner right armature, it replaces ground on the control lead over the following circuit: ground, left alternate contacts of relay 222, outer right normal contacts of relay 248, left alternate contacts of relay 257, inner left normal contacts of relay 211, inner right normal contacts of relay 238, contacts 235 of relay 226 to the control brush which is in contact with terminal C of the control lead. This replacing of the ground on the control lead prevents relay 309 from releasing at this time. The operation of relay 301, in ad-

dition to removing ground from the control lead as previously mentioned, also disconnects the tip and ring conductors 303 and 302 from the pulse relay 300 and extends them through the tip and ring brushes of the 70 switch which are now in contact with the called line.

The operation of relay 301 also extends ringing current through contacts 328 and 340 to relay 309 but as this relay is still held operated by ground on the control lead, the ringing current is not actually applied to the called line at this time. However, when the toll operator, observing the lighted supervisory lamp 125, rings in the usual manner 75 by operating ringing key 114, she thereby operates ring-up relay 258 (Fig. 2) which relay, in operating, closes an obvious energizing circuit for relay 248. Relay 248, in operating, opens at its outer right normal contacts, the ground connection previously traced for the control lead thereby causing relay 309 (Fig. 3) to release. This connects ringing current to the called line in the following circuit: generator, interrupter 343, contacts 328 of relay 301, left-hand winding of relay 309, contacts 329 of relay 309, contacts 330 of relay 312 and over the ring brush and terminal of the connector to one side of the called line, the other side of the line being 80 grounded at the outer right alternate contacts 340 of relay 301 through the top brush and terminal of the connector, middle right normal contacts 333 of relay 312, third outer normal contacts 342 of relay 309, outer right 85 alternate contacts 340 of relay 301 to ground. This ringing circuit is intermittently interrupted by interrupter 343 until the called subscriber answers, when the removing of the receiver from the rack causes direct current, 90 superimposed on the ringing generator as is the usual practice, to flow in the left-hand winding of relay 309 which of course is not responsive to the ringing alternating current. This direct current is sufficient to again operate this relay, which now in operating disconnects the ringing current from the line 95 and again locks up to the control lead.

As brought out in the statement of the invention, the contact springs of ring-up relay 105 258 are so adjusted that the inner springs are of very light tension and are closed on the first pulse of the ringing current, thereby preparing a locking circuit for ringing relay 248 which is completed when this relay operates. The outer contacts of relay 258, 110 however, have a heavier tension and do not close until the ringing current has fully magnetized the core of the relay. This phase of the invention is a decided improvement over 115 the usual ring-up relay arrangement which is liable to permit the ringing relay 248 to chatter, in case the ringing current received over the trunk is attenuated to such an extent 120 as to just barely operate the usual ring-up 125 130

relay which would then tend to follow the 16 cycle ringing current pulses. In this arrangement on the other hand the ring-up relay would under such circumstances, as soon as it has once attracted its heavy tension contacts, be held locked until the ringing ceases.

The removal of ground from the control lead by the opening of the outer right contacts of relay 248 is only momentary, as the 10 opening of this contact also acts to release relay 257, which relay, in retracting its left armature, again connects ground to the control lead independent of ringing relay 248. This connection can be traced from ground, 15 left alternate contacts of relay 222, left normal contacts of relay 257, inner left normal contacts of relay 211, inner right normal contacts of relay 238, contacts 235 of relay 226, the control brush and corresponding 20 terminal C of the control lead 308. Relay 257 is slow to release so that relay 309 of the connector circuit will release first. Therefore, it will be noted that when relay 309 is operated the second time as described 25 above when the subscriber removes his receiver from the hook in answer to the ringing, it will immediately find ground on the control lead and thus be maintained locked up independent of the fact that the toll operator 30 may still have the ringing key depressed and consequently relay 248 operated.

If, for some reason or other it should become necessary to recall the wanted subscriber while he is still connected to the line, 35 this may be done by having the toll operator depress the ringing key 114 and all operations would be the same as hereinbefore described up to and including the operation of relay 248, as the called subscriber's receiver will in this case be off the hook when relay 248 operates and the re-ringing current will be applied to the wanted subscriber through the operation of relay 211. Relay 211 is operated over an obvious circuit closed 40 by the operation of relay 241. That is, relay 241 operates when the subscriber's loop is completed over a circuit as follows: Battery, winding of relay 241, middle right-hand normal contacts 255 or relay 238, right-hand lower winding of repeating current 243, and back through the subscriber's loop to the upper right-hand winding of this coil to ground at the outer normal contacts 250 of relay 238. Relay 211, in operating, 45 connects ground at its inner alternate contacts to the control lead in the following circuit; ground, inner left alternate contacts of relay 211, inner right normal contacts of relay 238, contacts 235 of relay 226, control brush 50 and terminal C of the control lead 308, thereby preventing relay 309 from releasing. Relay 211, in operating, thus connects uninterrupted ringing current through the springs of relay 248 for transmission 55 over an obvious path to the called line.

It will be noted that when the toll operator decides to re-ring, relay 211 is already operated before relay 248 becomes operated and consequently, when relay 248 does operate, ringing current from the source at the inner right-hand armature and alternate contact of the relay 211 is already connected through to the middle left-hand armature of relay 248 and that the return ground is normally connected to the inner 75 left-hand armature of this relay through contact 261. It will therefore be seen that, due to the make-before-break or follow-up contacts 247, 252 of relay 248, the connection of ringing current to the associated subscriber's line will take place before the tip and ring leads are disconnected from the toll operator and the out-going end of the trunk line, so that no disagreeable clicks or other disturbances that would ordinarily 80 occur in circuits of this type during the change-over from the talking leads to the ringing source, will be present in the system designed in accordance with this invention.

In case the polarized 135 cycle relay 121 in the composite ringer associated with the calling toll should operate for any reason either falsely or due to the distant toll operator re-ringing the toll operator, the 16 cycle current applied at the springs of relay 126 will be sufficiently limited, either by the high resistance 127 or in any other suitable manner, so as to be incapable of operating the ring-up relay 258 although it is sufficient to operate the supervisory relay 100 104 of the toll operator's cord circuit.

In case the end of the toll cord is associated with a non-composited toll line such as L and the voltage of the ringing current measured across the terminals of ring-up relay 258 is such that this relay barely operates, relay 248 will not follow the ringing current causing chatter due to the assembly and adjustment of the contact springs of relays 258 and 248. As before mentioned, the inner springs of relay 258 are sufficiently flexible to close their contacts on very weak ringing current impulses, thereby preparing a locking circuit for relay 248, but due to the stiff adjustment of the outer springs of relay 258, these contacts will not be closed to operate relay 248 to lock it up unless the ringing current applied to relay 258 is of a certain value. It will, therefore, be noted that relay 248 cannot chatter in any event 115 as it is not operated unless the ringing current is strong enough to fully operate the ring-up relay 258. On the other hand if relay 248 is once energized, it locks up under control of the flexible contact springs of relay 258 which will remain closed throughout the ringing on any current value which is sufficiently strong to close the stiffer 125 springs of this relay.

In connection with the selection of sub- 130

scribers' lines by the operation of the rotary magnet 319 in response to the unit digit impulses the connector circuit shown in Fig. 3 is also designed to hunt automatically for an idle trunk of a group of trunks leading to a P. B. X. In the case, therefore, where the wanted subscriber is located at a P. B. X. and the first trunk selected leading to this exchange is busy, there will be ground on the sleeve and hunting terminals of that trunk. It should be noted that in accordance with this invention the sleeve and hunting terminals of the group of trunks leading to the P. B. X. except the corresponding terminals of the last trunk are strapped together. As shown in Fig. 3 the terminals of three P. B. X. trunks are shown, two of which have their sleeve and hunting terminals strapped and the other, which represents the last trunk in the group, has its sleeve and trunk terminals not strapped together but merely multiplied independently to other connector terminal banks in the usual manner.

Therefore, if the first P. B. X. trunk is busy, ground on the sleeve terminal will be supplied from the ground at the third left-hand armature and front contact of relay 301 of the connector used in this busy connection. The circuit for this ground may be traced through such a connector circuit as follows: Ground, third right-hand armature and front contact of relay 301, inner left-hand armature and back contact 326 of relay 312, inner right-hand armature and front contact 324 of relay 325, middle right-hand armature and back contact 321 of relay 320, sleeve brush S and the corresponding terminal through the strap from this terminal to the hunting terminal which will, therefore, also be supplied with ground from relay 301. The ground on the sleeve terminal of this trunk, therefore, causes relay 325 to be operated when the connector lands its brushes on the terminals of this P. B. X. trunk over the following circuit: Battery, winding of relay 325, contacts 322 of relay 320 to the sleeve terminal. This relay now locks up over the following circuit: Battery, winding of relay 325, fifth right-hand armature and back contact of relay 301, left-hand armature and front contact of relay 325, contacts 351 of relay 312 to the sleeve terminal S. This locking circuit is independent of the contacts of relay 320. As now relay 325 operates and relay 320 releases after the last interruption of the stepping circuit for the rotary magnet 319 a circuit is thereby closed for relay 336 due to the ground on the hunting lead as follows: Battery, winding of relay 336, armature and back contact of rotary magnet 319, inner left-hand armature and back contact of relay 336, outer right-hand armature and front contact of relay 325, inner right-hand armature and back contact of relay 320, outer right-hand armature and back contact of relay 312, middle right-hand armature and front contact of relay 325, outer right-hand armature and back contact of relay 325 to the ground on the hunting terminal. It should be observed that this relay 336 is under control of the rotary magnet 319 and closes an energizing circuit for this magnet 319 at its outer left-hand armature and front contact to ground at contacts 311 of relay 312 from the control lead 308. Rotary magnet 319 in energizing steps the brushes of the connector to the terminals of the next P. B. X. trunk. This circuit for energizing magnet 319 may be traced as follows: Battery, winding of relay 319, outer left-hand armature and front contact of relay 336, contact 311 of relay 312 to ground on the control lead 308. The rotary magnet 319 as stated controls the circuit for relay 336, which now is released and this relay in turn causes the release of magnet 319. If this next trunk is also busy, the operations described above are repeated, but if it is idle, there will be no ground on either the sleeve nor hunting terminals and relay 325, therefore, releases to close the circuit for relay 301, which operates and starts the various operations, resulting finally in the ringing of the connected P. B. X. operator in the same manner as for an ordinary subscriber hereinbefore described.

On the other hand, if the next terminals to which the brushes land are associated with the last trunk in the group leading to this particular P. B. X. and this trunk is busy, it becomes necessary to prevent the connector from operating further and bring the brushes thereof into connection with the first trunk of the next succeeding group of P. B. X. trunks or the next subscriber's line, as the case may be and also to cause the connector to give a busy signal to the toll operator, as an indication that all trunks of this particular P. B. X. are engaged. In this case relay 312 will operate as the sleeve and hunting terminals of this last trunk are not connected together and consequently there will be no ground on the hunting terminal but only on the sleeve terminal. Relay 312 is operated over a circuit as follows: Battery, winding of relay 336, armature and back contact of rotary magnet 319, inner left-hand armature and back contact of relay 336, outer right-hand armature and front contact of relay 325, inner right-hand armature and back contact of relay 320, winding of relay 312, contacts 351 of relay 312 to ground on the sleeve terminal S. Relay 326 does not operate in series with relay 312 as it is marginal in its operation. The operation of relay 312 transfers the holding circuit for relay 309 from the control lead to the sleeve lead 306 at its outer left-hand

armature and also closes an operating circuit for relay 301 as follows: From battery, through relays 336 and 312, inner left-hand armature and front contact of relay 312, contacts 327 of relay 301, left-hand armature and front contact of relay 309, left-hand winding of relay 301 to ground on the sleeve lead 306. Relay 301 in operating provides a locking circuit for itself as follows: Battery, winding of rotary magnet 319, winding of relay 320, armature and back contact of relay 318, upper alternate contacts of off-normal contact springs 317, right-hand winding of relay 301, inner right-hand armature and front contact of relay 301 to ground on the sleeve lead 306. Relay 301 in operating removes ground from the control lead 308 at its second right-hand armature and front contact 307, to complete the operations as will be hereinafter described. Relay 301 also completes the connection of leads 302 and 303 at its left-hand armature and front contacts to relay 312, which it will be noted is held up by ground from contacts of relay 301. Busy flash signals are now sent to the toll operator in the following manner.

As previously explained, ground is taken off the control lead 308 and consequently relay 238 is permitted to release. The release of this relay closes the circuit for relay 241 to ring lead 302, and when the interrupter 350 now interrupts the circuit for relay 241 and consequently also the circuit for relay 211. Relay 211 being intermittently operated removes and replaces battery on the trunk leading to the toll operator's circuit, and it will be seen that relay 212 will also be operated when relay 238 releases and the reversal of battery by this relay 312 will as hereinbefore described cause the operation of the signal 225 at the toll operator's position, and consequently the interruptions as caused by the interrupter 350 will cause the signal to flash and in this manner notify the operator that the wanted subscriber's line, or as in this case that all the P. B. X. operator's trunks, are busy.

Similar conditions will exist when the wanted subscriber's line is in communication with the toll operator and the subscriber decides to recall the operator, at which time the manipulations of the switchhook will alternately operate and release relay 241 and consequently cause lamp 125 to flash to indicate this condition to the toll operator. In releasing the connection, replacing of the subscriber's receiver on the hook will light lamp 125 steadily as hereinbefore described and the toll operator may then remove plug 107 from jack 200, thus releasing the various relays in the selector including relay 204, which results in the operation of the releasing magnet 208, over an obvious circuit through the right-hand armature and

back contact of relay 222. The circuit for the release magnet 208 opens at the off-normal contacts 228 when the switch has returned to normal. The release of the connector takes place when the release magnet 70 313 is operated on the release of the relay 309 which is due to the removal of the ground from the control lead 308. The circuit for the release magnet 330 may be traced as follows: Battery, winding of magnet 313, off-normal contacts 317, outer armature and back contact of relay 309, armature and back contact of relay 300, upper right-hand armature and back contact 310 of relay 301 to ground. This circuit for the release magnet 313 will open at the off-normal contacts 80 317 when the connector has returned to normal.

What is claimed is:

1. A marginal device for retransmitting 85 ringing currents comprising a relay having a slow-releasing armature responsive to weak currents, and a quick-acting armature responsive to strong currents, and a second relay responsive for its initial energization 90 to the operation of said quick-acting armature and for its continued energization responsive to said slow-releasing armature.

2. A relaying device for retransmitting 95 ringing current only above a certain predetermined value comprising a relay having a slow-releasing armature responsive to weak currents, and a quick-acting armature responsive only to strong currents and a second relay for transmitting ringing current 100 responsive for its initial energization to the said quick-acting armature of said first relay and responsive for its continued energization to said slow-releasing armature of said first relay.

3. A marginal device responsive to alternating current signals above a certain value comprising a relay having two armature springs of different stiffness and corresponding normally open contacts associated therewith, the operating characteristics of the relay being such that the weakest spring remains closed with its contact longer than the other spring with its contact after the energizing current has ceased to flow in the 115 winding of said relay, a second slow-to-operate relay having an operating circuit controlled by the stiffer spring and its contact, and a holding circuit controlled by the weaker spring and its contact, the operating characteristics of the two relays being such that if the operating alternating current maintains the stiffer spring operated for a certain period during a half-wave of current to cause the second relay to become 120 operated, said second relay will remain operated continuously as long as alternating current is applied.

4. In a telephone system, incoming lines, 125 outgoing trunks and subscribers' lines, an 130

operator's position and a cord circuit there-
at for connecting the incoming line with an
outgoing trunk, automatic switching means
for extending a connected trunk to a sub-
scriber's line, means for applying alternating
current of a certain value to the cord circuit
and a connected trunk, signaling means in
the operator's cord circuit responsive to
said alternating current, means in said cord
10 circuit for applying alternating current of a
certain other value to the connected trunk,
and signaling means in said trunks responsive
to the alternating current signals of the
last mentioned value only for signaling a
15 connected subscriber.

5. In a telephone system, subscribers' lines, an operator's position, a source of ringing current, means for controlling the application of ringing current from said source to a subscriber's line comprising a relay having a winding and normally closed contacts in the circuit from the source to the subscriber's line, and another winding for the locking of the relay when operated
20 to prevent the application of ringing current through the first mentioned winding, and means controlled by the operation thereof for the release of said relay for the ap-
25

plication of ringing current and for the locking up of the relay when it again operates to cut off the ringing current in response to the removal of the subscriber's receiver from the hook.

6. In a telephone system, subscribers' lines, a source of ringing current, means for controlling the operation and removal of ringing current from said source to a subscriber's line comprising a relay having a winding and a contact in the circuit from the source to the subscriber's line, another winding included in a circuit for holding said relay operated to prevent the application of ringing current, means for controlling said second circuit to release said relay for the application of ringing current, means for operating said relay to discontinue the application of ringing current in response to the subscriber removing the receiver from the hook, and means for controlling said second circuit to cause the locking of the relay after once operated regardless of the condition set up to apply ringing current.

In witness whereof, I hereunto subscribe my name this 8th day of April A. D., 1925.

RAY L. STOKELY.
